FRUIT JAR HOLDER

William I. Burns, Parnell, Mo.

Application June 10, 1933, Serial No. 675,216

8 Claims. (Cl. 81—3.3)

This invention relates to fruit jar holders and more particularly to a holder constructed for use in connection with the filling of fruit jars closely adjacent a stove or the like.

5 An object of this invention is to provide a fruit jar holder which embodies means for mounting the device at the side of a stove where the articles are being cooked, the device including means for holding the jar after it has been filled 10 so as to permit the tightening of the cap on the jar so as to seal the contents thereof.

Another object of this invention is to provide a holder of this type including clamping means for clamping the devices on a stove and also 15 including means whereby fruit jars or the like of varying sizes may be releasably clamped in the holder in a manner whereby to hold the jar against turning while the cap is being screwed or otherwise fastened on the top thereof.

20 The above and various other objects and advantages of this invention will in part be described and in part be understood from the following detailed description of the present preferred embodiment, the same being illustrated 25 in the accompanying drawing wherein:—

Figure 1 is a detail side elevation partly broken away of a device constructed according to the embodiment of this invention, showing the device in applied position on the side of a stove, the 30 stove being shown in fragmentary sectional form.

Figure 2 is a fragmentary front elevation of the device.

Figure 3 is a top plan view partly in section and partly broken away.

35 Figure 4 is a sectional view partly in detail taken on the line 4—4 of Figure 3.

Referring to the drawing wherein like numerals of reference designate corresponding parts throughout the several views, the numeral 10 40 designates generally a table or platform of desired size provided with upturned side portions 11 and 12. The inner ends of the sides 11 and 12 are each provided with elongated slots 13 through which a bolt 14 passes, and a clamping 45 member 15 is disposed one on each side of the platform or base 10 and engages against each side 11 and 12. These clamping members 15 have inclined outer edge portions 16 which confront a vertical edge 17 provided on an upstanding lug 18 integral with each side 11 and 12. The upper end of the clamping member 15 is 50 adapted to engage beneath the downturned edge portion of a stove so as to hold the base or platform 10 against outward movement relative to 55 the top of the stove.

A standard comprising a pair of bars 19 which have their upper ends secured as by bolts 20, depends from the base or platform 10 and is secured at a point outwardly from the inner end thereof. The lower portions of these bars 19 are bent inwardly, as at 21, and secured by rivets or other securing members 22 to a hollow or tubular standard 23. This tubular standard or leg has a telescoping member 24 extending upwardly thereinto provided with a foot 25, and this sliding member 24 is secured in adjusted position by means of a bolt or set screw 26. In this manner, the standard or support comprising the bars 19, 21, 23 and 24 coat with the clamping members 15 to hold the platform or 60 base 10 in substantially horizontal position.

A bracing member 27 extends between the two bars 19 intermediate the ends thereof and is provided with a plurality of apertures 28 at substantially the central point thereof within one of which a hook 29 integral with an elongated bracing member 30 is adapted to engage. The opposite end of the bracing member 30 is secured as by an eye 30a to the base or platform 19 adjacent the forward end thereof and contacts with the standard and the clamping members 15 to hold the platform 10 substantially horizontal. The upturned side member 11 has an extension 31 intermediate the ends thereof which is provided with a slot 32. The opposite side portion 12 has an extension 33 having a plurality of relatively large openings 34 and a relatively small opening 35.

A pair of jar clamping members, generally 90 designated as 36 and 37, are disposed between the sides 11 and 12. This clamping member 36 comprises a segmental member 38 which is held in vertical position between the sides 11 and 12 by an elongated bar having a pin 39 at one end thereof engaged in the aperture 35, and this bar is bent intermediate its ends about the outside of the clamping member 36 and is extended outwardly through the slot 32 so as to provide a handle 40. The pin 39 is preferably bent inwardly or toward the inner end of the platform 10 and in the direction opposite from the clamping member 37. The clamping member 37 is constructed similar to the clamping member 36 and is mounted in opposed relation thereto so that these two clamping members 36 and 37 will engage the periphery of a jar or other round object. These members 36 and 37 may be constructed as articulate members or any other desired shape to hold jars or articles which are either round or angular. 95

100 A handle 41 extends laterally of the clamping 105

110

member 37 and engages about the outside thereof and is provided on the opposite end with a head 42 which is adapted to be disposed through a selected aperture 34. The side 11 has along the 5 upper edge thereof a toothed rack 43 and the handle 41 has a pawl 44 which is adapted to engage between selected teeth of the rack 43 so as to hold the movable clamping member 37 in adjusted position relative to the fixed clamp- 10 ing member 36. Each clamping member 36 and 37 is provided on its inner face with a pad or cushioning member 45 which is secured to the inner face thereof by means of inwardly bent lugs 46. These cushioning members 45 have ser- 15 rated confronting faces 47 so as to more firmly grip the outer surface of a jar disposed between the two clamping members 36 and 37.

In the use of this device, the platform or table 10 is secured to one side of the stove by adjusting 20 the clamping members 15 beneath the rim or downturned flange of the stove. The supporting leg or standard can be adjusted as to height by means of the set screw 26 and the bracing member 30 then engaged in the desired aperture 28 25 of the horizontal bracing member 27. The fixed clamping member 36 is mounted in fixed position by disposing the reduced end portion 39 in the aperture 35 and the handle 40 engaged within the slot 32 of the side wall 11. The movable 30 clamping member 37 may initially have the outer end 42 disposed in the selected aperture 34 and the handle 41 moved away from the handle 40 with the pawl 44 resting on the rack 43. The jar may be placed between the two clamping 35 members 36 and 37 either before or after it has been filled, the device being so constructed that, if desired, the jar may be placed between the clamping members when it is empty and then filled, or where the articles being canned are 40 initially placed in the jars and the jars then placed in a hot container and the articles cooked, the hot jar with the articles therein may be placed between the clamping members 36 and 37, whereupon the movable clamping member 37 may 45 be swung toward the fixed clamping member 36, this being accomplished by moving the handle 41 toward the handle 40 with the pawl 44 riding over the teeth 43. The desired pressure can be applied to the clamping member 37 by pressing 50 the two handles 40 and 41 together or toward each other and then the cover or seal for the jar can be tightened to the desired degree.

It will be obvious from the foregoing that the 55 cover or seal for the jar may be tightened while the material in the jar is very hot and that the person using the device herein described will not burn or otherwise injure the hands during the canning operation. The platform 10 may, of course, be disposed in a horizontal position or, 60 if desired, may by means of the adjustable brace 30, be tilted downwardly toward its outer end so that any water or liquid disposed on this platform will flow away from the stove.

The fixed clamping member 36 is provided with 65 an L-shaped bracing member 48 which is adapted to engage against the inner side of the extension 31 and, if desired, a bolt or securing member may be placed through the bracing member 48 and through the extension 31 so as to firmly hold the clamping member 36 against horizontal and vertical movement.

It is, of course, understood that various changes and modifications may be made in the details of construction and design of the above specifically 75 described embodiment of this invention without

departing from the spirit thereof, such changes and modifications being restricted only by the scope of the following claims.

What is claimed is:—

1. A device as set forth comprising a table, 80 means carried by one end of the table for securing said one end to the side of a stove structure, a standard secured to the table outwardly of the inner end thereof and coacting with said first named means in holding the table in substantially horizontal position, a fixed clamping member, means for mounting said fixed clamping member on the table, a movable clamping member, and means for mounting said movable clamping member in adjusted position relative to the first 85 clamping member. 90

2. A device as set forth comprising a table, clamping means carried by the inner end of the table for engagement with the rim of a stove to secure said inner end of the table to said stove, 95 a standard, means for securing the standard to the table at a point intermediate the ends thereof, means for adjusting the length of the standard to hold the table in substantially horizontal position, an arcuate fixed jar clamping member, 100 means for mounting said fixed clamping member in upright position on the table, a movable arcuate jar clamping member, and means carried by the movable clamping member and the table to adjustably mount the movable clamping member 105 on the table for movement toward or away from the fixed clamping member.

3. A device as set forth comprising a table, means carried by the inner end of the table for securing said inner end to the rim of a stove, a 110 supporting standard for the table, means for securing the standard to the table at a point intermediate the ends thereof, means carried by the standard for adjusting the length thereof to hold the table in substantially horizontal position, a bracing member carried by the table and engaging the standard and coacting therewith to hold the table in substantially horizontal position, upturned side walls carried by the table one of said side walls having a plurality of lon- 115 gitudinally spaced apertures therethrough, the other of said side walls having a vertically ex- 120 tends slot therein opening through the upper edge, an arcuate fixed jar clamping member disposed between the two side walls, a handle se- 125 cured to said fixed clamping member and extend- 130 ing through said slot, a pin extending outwardly from said fixed clamping member through a se- 135 lected aperture in said one side wall, a movable jar clamping member, a handle for said movable jar clamping member, means carried by said movable clamping member engaging in another of said apertures in said one side wall to hold one side of said movable clamping member against movement, a toothed rack carried by the other 145 side wall on the upper edge thereof, and a pawl carried by the handle of said movable clamping member for engagement with the rack to hold the movable clamping member in adjusted position relative to the fixed clamping member.

4. A device as set forth comprising a table, a pair of upstanding members carried by said table in spaced parallel relation to each other, one of said members having spaced apertures there- 145 through, and a pair of clamping members be- tween said upstanding members, said clamping members each having a lug at one side engage- 150 able in a selected aperture, and means for holding said clamping members in clamped position about a jar.

5. A device as set forth comprising a table, a pair of upstanding members carried by said table in spaced parallel relation to each other, one of said members having a plurality of spaced apertures therethrough, the other of said members having a vertically disposed slot therein, a pair of clamping members disposed between said upstanding members, a lug carried by each of said clamping members and engageable in selected apertures of said one member, a handle carried by each clamping member and extending laterally of the table, one of said handles being engageable in said slot to hold one of said clamping members in a fixed position relative to the table and means carried by the other handle to releasably hold the other clamping member in clamped position about a jar.

6. A device as set forth comprising a table, a pair of upstanding members carried by said table in spaced parallel relation to each other, one of said members having spaced apertures therethrough, a pair of clamping members between said upstanding members, a lug carried by each clamping member and engageable in a selected aperture, the other of said upstanding members having a vertically extending slot therein, a handle carried by each clamping member and extending outwardly of the opposite side of each clamping member, one of said handles being engageable in said slot to hold said clamping member against movement, means for holding said table in a fixed position relative to a support and means for releasably holding the other clamping member in clamped position about a jar.

35 7. A device as set forth comprising a table, a pair of upstanding members carried by said table

in spaced parallel relation to each other, one of said members having a plurality of spaced apertures therethrough and the other of said members having a vertically extending slot therethrough, a pair of clamping members disposed between said upstanding members, a lug carried by each clamping member and engageable in a selected aperture, a handle carried by each clamping member and extending laterally of the table on the side opposite from said apertures, one of said handles being engageable in said slot to hold one of the clamping members in a fixed position, a toothed rack carried by the other of said upstanding members, and means carried by the other handle engageable with said rack to hold said other clamping member in adjusted position relative to said one clamping member.

8. A device as set forth comprising a table, a pair of upstanding members carried by said table in spaced parallel relation to each other, one of said members having spaced apertures therethrough, a pair of clamping members between said upstanding members, a lug carried by each clamping member and engageable in a selected aperture, a handle for each clamping member extending laterally of said table, the other of said upstanding members having a slot therein to receive one of said handles for holding one of said clamping members in a fixed position, a table supporting means pivoted to said table, means for releasably holding the other clamping member in clamped position about a jar, and means for holding said table in adjusted position relative to said support.
